REFRIGERATING APPARATUS

Walter Gilbert, Sr., Johnstown, Pa., assignor of
one-half to Ernest F. Walker, Johnstown, Pa.

Original application May 24, 1935, Serial No.
23,320. Divided and this application May 15,
1937, Serial No. 142,921

2 Claims. (Cl. 62—115)

This application is a division of my copending application, Serial Number 23,320, filed May 24, 1935.

This invention relates to a refrigerating system, and more particularly to a multiple system or system employing a plurality of cooling units operating at different temperatures for supplying the required amount of refrigeration, such cooling units being supplied with refrigerant from a single compressor condenser unit.

The invention may be utilized for example in an installation having a low temperature cooler to be maintained at a temperature at or below 0° F. and a display counter to be maintained at a temperature above freezing point, although it is not limited to systems of this character.

It is an object of the invention to provide improved control means for the cooling units for independently regulating the refrigerant supplied to each cooling unit by means of snap action thermostatically controlled expansion valves or the like and with additional means for preventing temperature equalization of the several cooling units by the flow of fluid from one to the other.

25 A further object of the invention is to provide a thermostatic expansion valve and operating mechanism therefor of improved construction and operating characteristics.

Other objects and advantages of the invention will appear from the following description of the embodiments thereof shown in the accompanying drawings, wherein:

Fig. 1 is a detail view partly in section of one form of the expansion valve embodying the invention;

Fig. 2, a fragmentary sectional view of a modified form of expansion valve, and

Fig. 3, a diagrammatic view of a system in which the valves shown in Figs. 1 and 2 may be employed.

Referring to Fig. 1 of the drawings, an expansion valve embodying the invention comprises a hollow, generally cylindrical sleeve member 10 provided with an extension or boss 11 at the upper end and closed at the lower end by a cap member 12 secured thereto in any desired manner, as by means of the bolts 13. Bracket members 14 and 15, depending from the sleeve member 10 are also clamped thereto by the bolts 13. An insulating disk 16 is secured to the lower ends of the bracket members 14 and 15, as for example by screws 18 threaded into the valve housing 19.

An expansible bellows 20 is clamped between the cap member 12 and the sleeve 10 and serves to seal the space 21 inside of the sleeve 10. The

space 21 is in communication through a length of tubing 22 with a capsule 23, the space 21, tubing 22 and capsule 23 being filled with an expansible fluid whereby the pressure exerted on the bellows member 20 is dependent upon the temperature to which the capsule 23 is subjected. The capsule 23 is positioned within or adjacent the refrigerating element or expansion coil of the refrigerating system in order to control the expansion valve in accordance with the temperature of the refrigerating element, as will be described hereinafter.

A piston 25 having a shank portion 26 surrounding a piston rod 27 is disposed within the bellows member 20 to be actuated upon an increase in pressure within the sleeve member 10. The movement of the piston 25 is resisted by a coil spring 28 arranged between the shank portion 26 of the piston and the threaded shank portion 29 of the thumb screw 30 threaded into the cap member 12. The piston 25 is biased by the spring 28 in an upward direction, the tension of the spring being adjustable by means of the thumb screw 30. A reinforcing sleeve 31 may be provided adjacent the bellows 20 and surrounding the spring 28 to prevent buckling of the bellows member. A pointer 32 cooperating with the thumb screw 30 permits the same to be calibrated in terms of operating temperatures.

A block 35 is secured on the piston rod 27 as 30 for example by means of clamping nuts 36 threaded on said rod. The block 35 is notched to form bearings for the knife edge links 37 and 38 forming a toggle link. The outer ends of the toggle link members 37 and 38 engage bearings in the supporting arms 39 and 40, the arm 40 being pivoted at 41 to the bracket member 14. The toggle link comprising the members 35, 37 and 38 is for the purpose of imparting a snap action to the thermostatically controlled member of the 40 valve and the tension of said toggle link is controlled by an adjustable spring 42 arranged between the pivoted arm 40 and a thumb screw 43 threaded upon the outer end of the portion 44 of the arm 39. By the described construction, a snap-action detent means is provided for the operating rod 27, the toggle link tending to hold the operating rod 27 in either its retracted or projected position until the pressure within the space 21 changes sufficiently to carry the block 35 past the dead center of the toggle. The critical temperature at which the thermostat will operate to effect movement of the valve operating rod 27 is adjusted by means of the thumb screw 30, in accordance with the calibration thereof or the 55

indications of the pressure gauge 24, whereas the difference between the actuating and restoring temperatures of the thermostat mechanism is controlled primarily by the thumb screw 43, although it will be understood that the latter element also controls the operating temperature of the thermostatic valve by reason of the reaction of the spring 42 upon the piston rod 27 in a direction to assist or oppose the tension of the 10 spring 28.

The operating rod 27 of the thermostatic mechanism is adapted to engage the valve operating plunger 47 which is slidably mounted in the insulating disk 16 upon an increase in the 15 temperature to which the capsule 23 is subjected which causes an increase in the pressure upon the piston 25 of the thermostat. The plunger 47 is operatively connected to a lever 48 pivoted at 49 within the valve housing 19 and having depending arms 50 engaging the head 51 of the expansion valve member 52. The valve member 52 is slidably supported in the valve housing and is normally biased to a closed position against the seat 53 by means of a spring 56. The spring 25 56 is held against the head 51 of the movable valve member 52 by means of a cap member 57 threaded into the valve housing. The opposite end of the valve housing is provided with an inlet connector 54 communicating with the valve 30 52 and 53 and adapted to be connected to the condenser or other source of refrigerant. The interior of the valve housing is connected through a pipe connection 55 to the refrigerating element or expansion coil with which the capsule 23 is 35 associated. Inspection of Fig. 1 of the drawings discloses that the internal diameter of the pipe 55, connecting the expansion valve housing with the refrigerating element or expansion coil, is substantially the same as the internal diameter 40 of the expansion valve orifice which adjoins the valve seat 53. This special design retards premature expansion of the refrigerant medium; that is, it retards expansion of the refrigerant medium prior to its reaching the refrigerating 45 element or expansion coil. This arrangement also makes for the elimination of frosting about the valve housing and permits installation of the entire evaporator assembly on the exterior of the cabinet to be refrigerated. The valve housing 50 19 is sealed at the top by a flexible diaphragm 58 clamped underneath the insulating disk 16.

It will be apparent that upon an increase in the temperature to which the capsule 23 is subjected, a pressure is built up in the thermostatic 55 element and the piston 25 is actuated thereby to throw the toggle 35, 37, 38 to the position shown in dotted lines in Fig. 1 and open the expansion valve 52, 53 to admit refrigerant to the cooling coil. As the temperature of the cooling 60 coil is lowered, the pressure in the capsule 23 decreases and at a predetermined temperature, the spring 28 restores the operating rod 27 to its initial position, thereby permitting the expansion valve to be closed by the spring 56 to 65 cut off the supply of refrigerant.

As shown in Fig. 2, the details of construction of the thermostatic mechanism may be varied without departing from the scope of the invention. In the construction shown in Fig. 2, the 70 bellows member 20 is replaced by an equivalent pressure-responsive construction. In this modification the thermostatic mechanism comprises a housing formed by the cap members 60 and 61. A diaphragm 62 corresponding to the bellows 75 member 20 of Fig. 1 is clamped between the cap

members 60 and 61. The space above the diaphragm 62 is in communication with a capsule located in or adjacent the cooling coils through the passage 63 and tube 64. The operating rod 65 for the expansion valve is secured to the diaphragm 62 by means of the clamping members 66, whereby the rod is actuated in response to changes in pressure to which said diaphragm is subjected. The movement of the piston rod 65 is opposed by the spring 67, the tension of which 10 is adjusted as desired by means of adjusting screw 68. The expansion valve which may be similar to that shown in Fig. 1 and the toggle link snap-acting mechanism may be supported upon the depending brackets 69 and 70, corresponding to the the members 14 and 15 in Fig. 1.

The snap-acting thermostatic expansion valve described above is designed for use in multiple refrigerating systems such as that shown diagrammatically in Fig. 3. The system shown in Fig. 3, by way of example, comprises a compressor 71, a condenser 72, a liquid receiver 73 and a plurality of refrigerating elements or expansion coils 74, 74a and 74b connected in multiple to the receiver 73. Expansion valves 75, 75a and 75b are connected to control the supply of refrigerant to the respective cooling coils, the expansion valve being of the construction shown in Fig. 1 or Fig. 2. By regulating these valves by means of the adjusting elements 30 and 43, the 20 temperatures of the cooling coils may be separately controlled and maintained between any desired limits, whereby a temperature may be maintained in one refrigerating compartment at or below 0° F. and in other compartments at the 25 same or different temperature, all of the cooling coils being supplied from a single compressor unit. Check valves 76, 76a and 76b are preferably provided between each of the cooling coils 74, 74a and 74b and the suction connection 77 of 30 the compressor 71.

In a system embodying the invention two or more refrigerators or evaporators may be maintained at separate or individual temperatures according to the requirements of each refrigerator 45 while all of the refrigerators may be supplied from a single condensing unit or compressing unit. The snap-acting thermostat control automatically maintains the desired temperature in each refrigerator without attention or supervision and by reason of the particular construction of the snap-acting mechanism, a positive operation of the expansion valves is insured at all 50 times.

Various modifications in the specific construction and arrangement of the valves shown may occur to those skilled in the art and are deemed to come within the scope of the invention if within the terms of the appended claims.

I claim:

1. In a multiple refrigeration system comprising a plurality of cooling units having individual evaporators connected with a compressor and condenser for the circulation of refrigerant, a snap acting expansion valve between said condenser and each evaporator, thermostatic means associated with each cooling unit for controlling each snap acting expansion valve, said each thermostatic means being constructed, arranged, and related to each snap acting expansion valve in a manner to cause said snap acting valve to open when the temperature of said cooling unit reaches a predetermined maximum and cause said snap acting valve to close when the temperature reaches a predetermined minimum.

suction lines from each of said evaporators connected with the suction side of said compressor, one-way valves disposed in said suction lines for preventing a back and interflow of refrigerant to and between any and all of the said evaporators by reason of back pressure in the suction lines, and as and for the purpose described said expansion valves constituting the sole expansion means between the condenser and each of the evaporators.

2. A refrigeration system comprising a compressor-condenser unit, a plurality of cooling units, a liquid line having connections for supplying refrigerant from the compressor-condenser unit to each of the cooling units, a return line to the compressor-condenser unit having connections with each of the cooling units,

a snap acting expansion valve in the supply lines to each of said cooling units for independently controlling the supply of refrigerant to each cooling unit, said each snap acting valve being adapted, constructed, and arranged to open in response to a predetermined high temperature and close in response to a predetermined low temperature, and a check valve in the suction line leading from each cooling unit for preventing return of refrigerant into the respective cooling units from the suction line and thereby equalizing or otherwise affecting the temperature of the cooling units said expansion valves constituting the sole expansion means between the condenser and each of the evaporators.
